[57] **CLAIM**

The ornamental design for an adjustable table, as shown
and described.

DESCRIPTION

FIG. 1 is a perspective view of an adjustable table
showing my new design.

FIG. 2 is a side elevational view.

FIG. 3 is a rear elevational view.

FIG. 4 is a top plan view.

FIG. 5 is a bottom plan view.

FIG. 6 is a perspective view showing the top pivoted to
an alternate position.

FIG. 7 is a perspective view of an adjustable table
showing a second embodiment of my design.

FIG. 8 is a top plan view of an adjustable table showing
a third embodiment of my design; and

FIG. 9 is a perspective view of the FIG. 8 embodiment
wherein the adjustable top has been pivoted to an alter-
nate position.

FIG. 1

FIG. 2

FIG. 3
